UNITED STATES PATENT OFFICE.

MORTIMER R. RUST, OF FULTON, NEW YORK.

BEATING-ENGINE LIGHTER-BAR.

1,304,604.

Specification of Letters Patent. Patented May 27, 1919.

Application filed November 23, 1918. Serial No. 263,860.

To all whom it may concern:

Be it known that I, MORTIMER R. RUST, citizen of the United States, residing at Fulton, in the county of Oswego and State 5 of New York, have invented certain new and useful Improvements in Beating-Engine Lighter-Bars, of which the following is a specification.

This invention relates to the particular 10 class of machines known as beating engines or rag engines, commonly used for the preparation of the stock or fiber for the manufacture of paper, paper board, roofing felt and other like products. It relates 15 more especially to that part of the beating engine or rag engine known as the lightering or lifting mechanism which serves as a support and means of adjustment for the beating roll.

20 The object of this invention is to provide devices for relieving the shocks and strains to which are subjected the lighter bars supporting the bearings of the beating rolls; to give elasticity to the parts carrying the 25 roll; to prevent damage to fly-bars and bedplates in beating engines and the like, by cushioning the fall of the beating roll after it has been raised from the bearings during the operation, either accidentally or 30 otherwise; to thereby afford a flexible, automatic adjustment of the beating roll to the bedplate, and thus preventing injury to the fiber by cutting, and, further, producing a more uniform quality of stock.

35 In the operation of beating engines with which this applicant is acquainted, the beating roll co-acts with and is adjusted with respect to a steel bedplate, and the roll is carried in bearings at either end, the bearings being supported on lighter bars. The

40 lighter bars are borne at either one or both ends by means of screws affording a vertical adjustment for regulating the position of the roll and its pressure on the bedplate.

45 In practice it often occurs that lumps of pulp, bundles of rags or other accumulated material passing between the roll and bedplate lift the roll out of the bearings and then allow it to drop back, thus producing a 50 strain or shock to the lighter bars and not infrequently breaking those parts. It is an object of this invention, by means of springs, rubber or other cushioning material, to produce a yielding resistance to

shocks to which the lighter bars are exposed 55 as explained, and to carry the beating roll in such manner that if suddenly lifted its bearings will follow it up and the impact of its return to its position will be cushioned and gradual. It is a further object 60 of this invention to produce mechanism which by balancing a portion of the weight of the beating roll with suitable cushioning material and devices, will produce an adjustment of the roll to the bedplate so that 65 if the flow of stock between the roll and bedplate is lumpy or uneven the roll will be automatically adjusted up and down, thus preventing the injury of the fiber by cutting, and resulting in a more uniform grade 70 of stock.

The stated objects are accomplished by means of the construction and arrangement of the parts illustrated in the accompanying drawing, of which Figure 1 represents a 75 side view of a beating engine provided with this invention. Fig. 2 is a side view of a lighter bar stand as shown in Fig. 1 with the roll bearing removed. Fig. 3 is a side view of a lighter bar stand as set out in 80 Fig. 2 with the roll bearing and box, the saddle, one of the levers, and the spring acting thereon removed. Fig. 4 is a side view of the saddle, and Fig. 5 is an end view thereof. Fig. 6 is a side view of one of the 85 levers with a portion broken away to disclose the half-cylindrical transverse portion that engages the fulcrum. Fig. 7 is an end view of one of the levers. Fig. 8 is a cross-section of the roll bearing and bearing box. 90

Throughout the drawings and description the same letter is used to refer to the same part.

Considering the drawings, the roll shaft A is supported in the bearing *a* carried by 95 the bearing box B, which has the depending flanges, such as the flange *b*, which admit the lighter bar C between them. The bearing box is carried by the curved saddle D, which passes between the flanges of the bearing box, adjacent to the edge of the lighter bar located also between the flanges of the bearing box. The saddle has the shoulders E and *e*. As stated, the saddle carries the bearing box, and the saddle itself 100 is upheld by the contact between the ends of the levers F and G and the shoulders of the saddle, as best illustrated in Fig. 1.

Both levers are alike. As shown in Figs. 6 and 7 the levers have side flanges, such as the flanges H and h of the lever F, and each lever has a part-cylindrical transverse 5 protuberance J extending between the flanges which engages the fulcrum K on the lighter bar.

The outer end of each lever has a cross-wise groove L, which engages the rounded 10 transverse lug M of a rocking disk or spring seat plate m. A vertical rod N with its lower end secured to the lighter bar passes upwardly through the plate m, and through the coil spring O, cap disk P, and thumb-nut Q that engages the upper end of the 15 rod N. By means of the thumb-nut the tension of the spring may be altered. The parts just described are duplicated for the other lever, as will be readily understood from 20 the drawings.

Considering Figs. 2 and 3, it will be observed that the middle portion of the upper edge of the lighter bar C is divided in the direction of the length of the lighter 25 bar, and provided with two curving sides or extensions R and r spaced apart. The curved body of the saddle D occupies and is freely movable in the space between the curving sides R and r.

30 In explaining the operation of this invention, let it be assumed that a lump of stock or bundle of rags has lifted the roll shaft upwardly out of its bearings. A part of the weight of the roll and its shaft has 35 been balanced by the adjustment of the tension of the coil springs which act upon the long legs of the levers, and, when the shaft is lifted the levers raise the saddle, bearing box and bearing accordingly. In other 40 words, as previously stated, the bearings follow the shaft up, and when the roll and shaft descend, the force of the springs acting through the levers cushions the fall of the shaft and renders the same in a measure 45 gradual. Injury to the roll or any portion of its structure is effectively prevented.

Having now described this invention, and explained the mode of its operation, what I claim is:—

50 1. In a beating engine, the combination with a lighter bar, of a roll shaft, a roll shaft bearing movable with the lighter bar, and means for cushioning the said bearing. 2. In a beating engine, the combination 55 with a lighter bar, of a roll shaft, a movable roll shaft bearing carried by the lighter bar, and means for cushioning the said bearing.

60 3. In a beating engine, the combination with a lighter bar, of a roll shaft, a movable roll shaft bearing carried by the lighter bar, means for cushioning the said bearing, and means for altering the tension of the said cushioning means.

4. In a beating engine, the combination 65 with a lighter bar, of a roll shaft, a movable roll shaft bearing, and means for cushioning the said bearing including a lever, and adjustable spring devices arranged to act upon the lever.

5. In a beating engine, the combination 70 with a lighter bar, of a roll shaft, a movable roll shaft bearing, and means for cushioning the said bearing including a lever fulcrumed upon the lighter bar, and adjustable 75 spring devices arranged to act upon the lever.

6. In a beating engine, the combination 80 with a lighter bar, of a roll shaft, a roll shaft bearing box, a saddle supporting the said box, and means for cushioning the saddle.

7. In a beating engine, the combination 85 with a lighter bar, of a roll shaft, a movable roll shaft bearing, a saddle supporting the bearing, and means acting upon the lighter bar for cushioning the saddle.

8. In a beating engine, the combination 90 with a lighter bar, of a roll shaft, a roll shaft bearing, a saddle carrying the said bearing, means for cushioning the said saddle including a lever fulcrumed upon the lighter bar, and adjustable spring devices borne by the lighter bar and arranged to act upon the lever.

9. In a beating engine, the combination 95 with a lighter bar, of a roll shaft, a roll shaft bearing box having dependent side flanges admitting the edge of the lighter bar between them, a saddle carrying the bearing box and passing between the said flanges of the box, and means for cushioning the saddle.

10. In a beating engine, the combination 100 with a lighter bar, of a roll shaft, a roll shaft bearing box having dependent flanges admitting the edge of the lighter bar between them, a saddle carrying the said bearing box and passing between the said flanges, means for cushioning the said saddle, and means for modifying the tension of the cushioning means.

11. In a beating engine, the combination 115 with a lighter bar, of a roll shaft, a roll shaft bearing having dependent flanges admitting the edge of the lighter bar between them, a saddle carrying the said bearing and passing between the said flanges, means for cushioning the saddle upon the lighter bar including a lever fulcrumed upon the lighter 120 bar, and adjustable spring devices arranged to act upon the lighter bar and upon the lever.

12. In a beating engine, the combination 125 with a lighter bar of a roll shaft, a roll shaft bearing, and means for cushioning the said bearing including twin levers fulcrumed upon the lighter bar and each lever having

side flanges admitting the edge of the lighter bar between them, and springs arranged to act upon the levers.

13. In a beating engine, the combination with a lighter bar, of a roll shaft, a roll shaft bearing, a saddle for supporting the said bearing and having shoulders at either end, levers fulcrumed upon the lighter bar and arranged to act upon the shoulders of the saddle, and springs arranged to act upon the said levers.

14. In a beating engine, the combination with a lighter bar, of a roll shaft, a movable roll shaft bearing carried by the lighter bar, and means borne by the lighter bar for cushioning the said bearing.

15. In a beating engine, the combination with a lighter bar, of a roll shaft, a roll shaft bearing box, a saddle supporting the

said box, and means borne by the lighter bar for cushioning the said saddle.

16. In a beating engine, the combination with a roll shaft bearing, of a lighter bar having portions spaced apart laterally with respect to the lighter bar and located at the upper edge of the lighter bar, and means for supporting the bearing having a member movably located between the said laterally spaced portions of the lighter bar.

17. In a beating engine, the combination with a roll shaft bearing, of a lighter bar having spaced side portions near its upper edge, a saddle for supporting the bearing and having a portion movably located between the said spaced side portions of the lighter bar.

In testimony whereof I affix my signature.

MORTIMER R. RUST.
